UNITED STATES PATENT OFFICE.

JOSEPH STRAND, OF LOS ANGELES, CALIFORNIA, ASSIGNOR TO KLINCH LATH CORPORATION, OF LOS ANGELES, CALIFORNIA, A CORPORATION OF CALIFORNIA.

WALL-BOARD RETAINER.

Application filed December 6, 1926. Serial No. 152,873.

My invention relates to the building industry, and it comprehends a unique wall board retainer which may be advantageously used in building plastered walls and partitions.

Wall board to a considerable extent has replaced the lath in wall and partition structures, since it is more economical both in first cost and installation. Such wall board 10 is commonly secured in place either by nails or a special retaining piece.

It is an object of this invention to provide a wall board retainer for the use designated above which embodies a pair of L-shaped 15 members which are fastened together to form substantially a Z-shaped retainer but to have a double thickness web.

It is another object of my invention to provide a wall board retainer and a tongue integral with one thickness of the web and formed at the free edge of a thickness opposite the flange of this member so that one edge of the tongue is in the plane of the mentioned edge.

It is a further object of my invention to provide a wall board retainer having a tongue which is so positioned that it may be conveniently engaged by an instrument and easily removed into an extended position in disposal 30 to hold a wall board against an opposite flange.

Other objects and advantages of my invention will be evinced hereinafter.

Referring to the drawing in which I illustrate my invention,

Fig. 1 is a horizontal section taken through a structure in which my wall board retainer is used.

Fig. 2 is an enlarged fragmentary perspective view showing clearly my invention and the manner in which wall boards are secured together.

Fig. 3 is an enlarged horizontal section showing clearly the construction of my invention.

The form of my invention shown in the drawing embodies a primary member 11 having a primary plate 12 from which there extends at right angles thereto a primary flange 13, and a secondary member 15 having a secondary plate 16 from which there extends at right angles thereto a secondary flange 17. The primary and secondary members 11 and 15 are secured together by rivets 19. These rivets 19 extend through the primary and sec-

ondary plates 12 and 16, securing the primary and secondary members together so that adjacent faces of the primary and secondary plates contact each other. The primary and secondary plates 12 and 16 form a central vertical web 20. The primary flange 13 extends outwardly from and at right angles to the central web 20 and the secondary flange 17 extends outwardly from the opposite edge of the central web 20 and substantially at right angles thereto, but in a direction opposite to the extension of the primary flange 13.

Formed at a free edge 22 of the primary plate 12 which is that edge opposite from the primary flange 13, is a series of primary tongues 23. These tongues 23 are formed so that outer edges 24 thereof are in the same plane as the free edge 22 of the primary plate 12. At a free edge 26 of the secondary plate 16, which free edge is opposite from the secondary flange 17, a series of secondary tongues 27 is formed. Outer edges 28 of these tongues 27 are formed in the same plane as the free edge 26 of the secondary plate 16. The primary and secondary tongues 23 and 27 normally rest in a position shown at the upper part of Fig. 2, so that they are only slightly out of line with the central web 20.

In using the retainer of my invention a plaster board 30 is placed so that one edge thereof engages either the primary or secondary flange 13 or 17. After the board 30 has been thus placed the tongues 23 or 27, which cooperate with the flange against which the board is placed, are moved into extended position which is substantially at right angles to the web 20. When the tongues are in extended position, as shown in the drawing, they cooperate with either of the flanges 13 or 17 to retain the wall board firmly in place. After the first wall board has been placed and secured by an extending of the tongues a second wall board is secured to the retainer, and so on.

When the wall board retainer is used as shown in Fig. 1 at a column 32, only one of the members which comprise it is used, that is, either the primary or secondary member 11 or 15 is dispensed with and the plate of the member used is secured directly against the column 32. When the wall board retainer is used in a wall employing studs, as indicated at 34, one of the flanges thereof is secured to an adjacent face of the stud 34. When the wall board retainer is employed in a parti-

tion which does not use studs, the retainers are secured at their lower and upper ends to floor and ceiling pieces and have an aspect as shown in the lower part of Fig. 1 and 5 Figs. 2 and 3.

After the wall boards have been installed a plaster coating 36 is applied to both sides of the wall board as shown in Figs. 1 and 3.

By making my wall board retainer in two 10 members it is possible for me to provide a superlative wall board retainer. The two members when secured together present a web which is of double thickness and very rigid, this rigidity helping to make a strong wall 15 or partition. The stamping of the separate members is quite facile and economical. One very profitable advantage of my invention resides in the ability to make the tongues of the wall board retainer connect with the free 20 edges of the primary and secondary members. By such arrangement the tongues may be easily bent into extended position because an implement, for example a screw driver, may be inserted directly between the tongues and 25 the plate of the opposite member. When the tongues are not formed at the edge of the web of the wall board retainer, it is rather cumbersome to insert a tool into a position suitable for extending them.

30 I claim as my invention:

1. A wall board retainer consisting of: a primary member having a primary plate and a primary flange formed at one edge of said primary plate; a secondary member having a 35 secondary plate and a secondary flange extending from one edge of said secondary plate; means for fastening said primary and said secondary plates together, said primary and secondary members defining a substantial Z-shape; primary tongues formed in said primary plate in connection with a free edge of said primary plate; and secondary tongues formed in said secondary plate in connection with a free edge of said secondary plate.

45 2. A wall board retainer consisting of: a primary member having a primary plate and a primary flange formed at one edge of said primary plate; a secondary member having a secondary plate and a secondary flange extending from one edge of said secondary plate; means for fastening said primary and said secondary plates together, so that said primary and secondary plates provide a web from the opposite edges of which said primary and secondary flanges extend in substantially opposite relative directions; primary tongues formed in said primary plate in connection with a free edge of said primary plate; and secondary tongues formed in said secondary plate in connection with a free edge of said secondary plate.

55 3. A wall board retainer consisting of: a primary member having a primary plate and a primary flange formed at one edge of said

primary plate; a secondary member having a 65 secondary plate and a secondary flange extending from one edge of said secondary plate; means for fastening said primary and said secondary plates together, said primary and secondary members defining a substantial Z-shape; primary tongues formed in said primary plate, one edge of each primary tongue being in the plane of a free edge of said primary plate; and secondary tongues formed in each secondary plate, one edge of 70 said secondary tongue being in the plane of a free edge of said secondary plate.

4. A wall board retainer consisting of: a primary member having a primary plate and a primary flange formed at one edge of said primary plate; a secondary member having a secondary plate and a secondary flange extending from one edge of said secondary plate; means for fastening said primary and said secondary plates together, so that said primary and secondary plates provide a web from the opposite edges of which said primary and secondary flanges extend in substantially opposite relative directions; primary tongues formed in said primary plate, one edge of each primary tongue being in the plane of a free edge of said primary plate; and secondary tongues formed in said secondary plate, one edge of each secondary tongue being in the plane of a free edge of said secondary plate.

5. A wall board retainer comprising: two angle iron members, each having a base flange joined at one edge with a wing flange; means for fastening said base flanges together when 10 said members have been placed together back to back so that said wing flanges extend in opposite directions; and tongues formed in said base flanges along free edges thereof, said tongues normally lying substantially in the 105 plane of the flange in which they are formed but being flexible outwardly in planes substantially parallel with said wing flanges.

6. A wall board retainer comprising: two angle iron members, each having a base flange joined at one edge with a wing flange; means for fastening said base flanges together when said members have been placed together back to back so that said wing flanges extend in opposite directions and in offset relation to 110 each other so that the cross section of said retainer is substantially Z-shaped; and tongues formed in said base flanges along free edges thereof, said tongues normally lying substantially in the plane of the flange in 115 which they are formed but being flexible outwardly in planes substantially parallel with said wing flanges.

In testimony whereof, I have hereunto set my hand at Los Angeles, California, this 30th 120 day of November, 1926.

JOSEPH STRAND.
